UNITED STATES PATENT OFFICE.

LEO T. SHEHEEN, OF HORNELL, NEW YORK.

GARMENT-PRESSING MACHINE.

Application filed January 7, 1921. Serial No. 435,604.

To all whom it may concern:

Be it known that I, LEO T. SHEHEEN, a citizen of the United States, residing at Hornell, in the county of Steuben and State of New York, have invented new and useful Improvements in Garment-Pressing Machines, of which the following is a specification.

This invention relates to a machine for 10 pressing garments and has for its object the provision of simple and efficient means for automatically locking the upper presser head down upon the lower presser head until released by hand.

15 In the accompanying drawings:

Figure 1 is a perspective view of a garment pressing machine embodying my improvements, showing the upper presser head lifted from the lower presser head. Figure 2 is a fragmentary vertical transverse section of the same. Figure 3 is a fragmentary vertical section of the same.

Similar characters of reference indicate corresponding parts throughout the several views.

10 represents the main frame of the machine which may be of any suitable construction to support the several working parts. 11 is the lower presser head or pad upon which the garment to be pressed is supported and 12 the upper presser head or pad which is movable vertically toward and from the lower head for pressing and releasing the garment between the same. 20 These heads may be heated in any suitable manner for facilitating the pressing operation in a well known manner. In the construction shown in the drawings, the upper presser head is actuated by means which comprise a vertically-swinging upper lever 13 preferably of forked form pivoted at 14 on the upper part of the main frame and supporting on its front arms the upper presser head, a lower intermediate lever 15 pivoted at 16 to swing vertically on the lower part of the main frame, and an upright link 17 connecting the rear arm of the upper lever with the rear arm of the lower lever. The lower intermediate lever 25 is preferably provided on the upper side of its front arm with a widened surface 18 which is formed by a plate having depending ears 19 secured by a bolt 20 to the lower lever.

30 The upper and lower levers 13 and 15 are turned and normally held yieldingly in a

position in which the upper presser head is elevated by a spring 22 connecting the rear arm of the upper lever with the front arm of the lower lever, as best shown in Fig. 2.

My improved automatic locking device 35 comprises a hand operated locking lever which is pivoted between its upper and lower arms to swing vertically on a bracket 23 which projects forwardly from the main frame, the upper arm 24 being nearly vertical while said lower arm is of elbow form and has an inner upright part 25 and terminates in a lower locking foot 26 which 40 projects forwardly from the part 25. On the plate 18 of the lower lever is mounted a locking loop 27 which is connected by a swivel joint with this plate, so that this loop can tilt forwardly and backwardly. 45 This swivel connection preferably consists of two downwardly-projecting bolts 28 on the loop arranged loosely in openings in the plate 18 and provided below the latter with stop nuts 29.

50 In the normal position of the locking device when the upper presser head is lifted from the lower head the locking lever is turned so that its upper arm is moved rearwardly and its lower arm is moved forwardly and causes the foot 26 to slide forwardly in the loop and project with its front end beyond the front edge of the plate 18, as shown in Fig. 1. Upon pulling the upper arm of the locking lever forwardly 55 the foot slides rearwardly through the loop on the lower lever and depresses the latter by engagement of the front end of the foot with the upper side of the plate 18. During this time the loop rocks on this plate, 60 this being permitted by the swivel joint between these two members and when the foot reaches the end of its rearward motion, the rear part of the upper side of this foot engages with the rear corner of the loop and 65 the lower front corner of the front end of the foot engages with the top of the plate, as shown in Figs. 2 and 3, thereby forming a clutch or grip which automatically locks 70 these parts in this position until again released by hand, thereby holding the upper presser head down on the lower presser head without any further attention on the part of the operator.

75 Upon pushing the upper arm of the locking lever rearwardly, the parts are again restored to their normal position in which the

upper presser head is lifted from the lower head.

This automatic locking device is exceedingly simple in construction, it is very efficient in operation, and the same can be readily applied to pressing machines already in use.

- It is sometimes desirable to operate the upper presser directly by hand particularly 10 when finishing the details of the pressing operation or when certain parts need touching up or require special attention. In order to permit of doing this easily, conveniently and readily the rear link is preferably made of sections, the upper section 30 being pivoted at 31 to the rear arm of the upper lever and the lower section 32 having the form of a tube which receives the upper section and is pivoted at 33 on the 20 lower lever. When operating the upper presser head through the medium of the link 17 and associated parts the two sections 30, 32 of the same are coupled by a coupling pin or bolt 34 sliding in a guide 35 on the 25 tube section and engaging its inner rear end with a notch 36 in the rod section 30. The coupling pin is yielding held in this position by means of a shifting lever 37 pivoted at 38 on the tube link section and having a 30 lower vertical arm 39 which is connected with the coupling pin, and a push spring 40 interposed between the upper arm 41 of the shifting lever and the tube link section. 35 The direct lowering and raising of the upper presser head is usually effected by a handle 42 mounted on the upper front part of the same. For the purpose of permitting the sections 30, 32 of the upright to be conveniently uncoupled when direct operation 40 of the upper presser head is desired a controlling handle 43 is pivoted on the upper front part of the upper presser head adjacent to the handle 42 which controlling handle is 45 operatively connected with the coupling pin 34 by an elbow lever 44 pivoted concentrically with the upper lever 13 and having a lower arm connected by a rod 45 with a horizontal arm 46 on the lever 37 while the upper arm of this elbow lever is connected by a rod 47 with the controlling handle, as best 50 shown in Fig. 2.

I claim as my invention:

1. A garment pressing machine comprising a main frame, a lower fixed presser head mounted on the frame, an upper presser head movable vertically toward and from the lower head, and means for actuating the

upper presser head comprising an intermediate lever operatively connected with the upper head, a loop mounted on said intermediate lever, and a hand lever pivoted on the frame and having an angular arm which engages with said loop.

2. A garment pressing machine comprising a main frame, a lower fixed presser head mounted on the frame, an upper presser head movable vertically toward and from the lower head, and means for actuating the upper presser head comprising an intermediate lever operatively connected with the upper head, a loop connected by a swivel joint with said intermediate lever, and a hand lever pivoted on the main frame and having a lower angular arm adapted to slide 70 in said loop and to grip said loop and intermediate lever on its upper and lower sides. 75

3. A garment pressing machine comprising a main frame, a lower fixed presser head mounted on the frame, an upper presser head movable vertically toward and from the lower head, and means for actuating the upper presser head comprising an intermediate lever operatively connected with the upper head, a loop connected by a swivel joint with 80 said intermediate lever, and a hand lever pivoted on the main frame and having an L-shaped lower arm the extremity of which is perpendicular to the radius of said hand lever and is adapted to slide in said loop and 85 also to grip with its upper side against the rear corner of said loop and to grip the underside of its front end against the top of 90 said intermediate lever.

4. A garment pressing machine having 95 a lower presser head, an upper presser head movable toward and from the lower presser, means for operating said upper head directly, means for operating said upper head indirectly comprising an 100 upper lever carrying the upper presser head, a lower lever, a link connecting said levers and composed of sections, and means for 105 coupling and uncoupling said sections comprising a coupling pin mounted on one of said link sections and engaging with a notch in the other link section, a shifting lever connected with said pin and pivoted on the same link section which carries said pin, a controlling handle pivotally mounted on 110 said upper presser head, and an elbow lever pivoted on the same axis as said upper lever and having one of its arms connected with said shifting lever and its other arm connected with said controlling handle.

LEO T. SHEHEEN.
